UNITED STATES PATENT OFFICE

156,315

COMBINATION DOOR LOCK AND BOTTLE OPENER

Charles M. Brazelton, Waco, Tex.

Application July 28, 1947, Serial No. 140,564

Term of patent 3½ years

(Cl. D44—29)

To all whom it may concern:

Be it known that I, Charles M. Brazelton, a citizen of the United States, residing at Waco in the County of McLennan, State of Texas, have invented a new, original, and ornamental Design for a Combination Door Lock and Bottle Opener, of which the following is a specification, reference being had to the accompanying drawing, forming part thereof.

Figure 1 is a perspective view of a combination door lock and bottle opener, showing my new design;

Figure 2 is a side elevational view;

Figure 3 is an end elevational view;

Figure 4 is an opposite end elevational view, and

Figure 5 is an edge view thereof.

I claim:

The ornamental design for a combination door lock and bottle opener, as shown,

CHARLES M. BRAZELTON.
